UNITED STATES PATENT OFFICE.

HERMAN E. KUHNER, OF OXFORD, MARYLAND; ROSE L. KUHNER EXECUTRIX OF
SAID HERMAN E. KUHNER, DECEASED.

LOCKING VALVE.

1,131,065.

Specification of Letters Patent. Patented Mar. 9, 1915.

Application filed January 23, 1914. Serial No. 813,968.

To all whom it may concern:

Be it known that I, HERMAN E. KUHNER, a citizen of the United States, residing at Oxford, in the county of Talbot and State 5 of Maryland, have invented certain new and useful Improvements in Locking Valves; and I do hereby declare the following to be a full, clear, and exact description of the invention, such as will enable others skilled in 10 the art to which it appertains to make and use the same.

This invention relates to valves used on motor cars to regulate the supply of gasoline to the engine; and it consists of a self-locking device for closing the valve at will and preventing it from being re-opened without the use of a special key. This device is intended to be used when a motor car is desired to be put out of action. For 15 instance, when a driver leaves the car by itself he can close the valve instantaneously, and the car cannot be operated by anyone who might attempt to steal it, and who was not provided with the necessary key.

20 In the drawings, Figure 1 is a side view, partly in section, of a plug valve provided with a locking device according to this invention. Fig. 2 is a plan view of the same.

The gasoline inlet pipe 2 is provided with 25 an inlet valve 3, and this valve is preferably a plug valve of any approved construction. A frame 4 is secured to the pipe and valve in any convenient way, and it is preferably secured to the valve. One tubular end portion of the valve casing has a collar 5 which abuts against a lug 6 on the frame, and the other tubular end portion is elongated and is secured to the frame by a clamping plate 7 and screws 8. The screws 8 are placed in 30 a position where they are not readily accessible after the complete device has been put together, to prevent the clamp from being removed in order to open the valve. The plug of the valve has a toothed segment 10 formed on or secured to it, and 12 is a toothed rack which gears into the said segment. The segment 10 has a guard-plate 14 on one side which overlaps the teeth of the rack and prevents the teeth of the segment 45 from being slid out of gear with the rack teeth. The toothed rack is formed on one side of a push-bar 15, which is U-shaped or channel-shaped in cross-section. The bar 15 is 50 slidable vertically in a guide 16 on the frame, and it is provided with a foot-plate

17 at its top above the level of the top of the frame. A lug or abutment 18 projects laterally from the frame into the channel of the bar, and a helical spring 19 is arranged between the lug 18 and the foot-plate 17. 60 This spring normally holds the push-bar in its raised position with the valve open, so that the gasoline can be supplied to the engine of the motor car.

A beveled tooth 20 projects from one side 65 of the bar 15, and 21 is a spring-actuated catch or bolt which is slidable in a socket 22 on the frame. This catch or bolt 21 is normally arranged below the level of the locking-tooth, and when the foot-plate is depressed to close the valve, the locking-tooth slides past the locking-bolt so that the return of the push-bar is prevented, and the valve is locked in its closed position. A suitable key-hole 24 is formed in the socket 22, 70 and a specially constructed key is provided for retracting the locking-bolt or for permitting it to be retracted. Any approved key device may be utilized for this purpose. The top of the frame is preferably arranged 75 on the floor line of the motor car.

The gasoline valve can be closed suddenly by a single movement of the foot or hand of the driver should the car be held up by 80 thieves, and they will be unable to drive away with the car on account of the gasoline supply being cut off.

What I claim is—

1. The combination, with a horizontal supply pipe, and a valve secured thereto; of a frame secured to and supported by the said parts and provided with a vertical guide and a horizontal socket, a push-bar 90 slidable in the guide and having a foot-plate at its top and a laterally projecting tooth, a spring which normally holds the foot-plate raised and the valve open, intermediate operating mechanism between the push-bar and the valve, and an automatic catch 95 slid-able in the said socket and engaging with the said tooth and holding the valve closed when the foot-plate is depressed.

2. The combination, with a frame pro- 105 vided with a guide and a lug arranged at opposite ends of said frame, of a valve pro- vided with a casing having horizontal tu- bular end portions one of which engages 110 with the said lug, a clamp which secures the other end portion to the frame, a push-bar having a foot-plate at its top and slid-able

vertically in the said guide, intermediate 5 operating mechanism connecting the push-bar with the valve, a spring which slides the push-bar in one direction and normally holds the valve open, and a catch which engages automatically with the push-bar when it is slid in the reverse direction to close the valve.

3. The combination, with a frame provided with a guide and an abutment, of a valve secured to the frame, a hollow push-bar slideable in the guide and having a foot-plate at one end, a spring arranged in the

push-bar between its foot-plate and the said abutment, intermediate operating mechanism connecting the push-bar with the valve, and a catch which engages automatically with the push-bar when it is slid forcibly against the pressure of the said spring to close the valve. 15 20

In testimony whereof I have affixed my signature in the presence of two witnesses.

HERMAN E. KUHNER.
